DESIGN FOR A HYDRAULIC PRESS

Relza J. Hess and Robert K. Sedgwick,
Chicago, Ill.

Application October 20, 1944, Serial No. 116,132

Term of patent 14 years

(Cl. D63—1)

To all whom it may concern:

Be it known that we, Relza J. Hess and Robert K. Sedgwick, citizens of the United States, residing at Chicago, Illinois, have invented a new, original, and ornamental Design for a Hydraulic Press, of which the following is a specification, reference being had to the accompanying drawings, forming a part thereof, wherein:

Figure 1 is a front elevation of a hydraulic press showing our new design;

Figure 2 is a side elevation thereof;
Figure 3 is a rear elevation thereof; and
Figure 4 is a top plan view thereof.

We claim:

The ornamental design for a hydraulic press, substantially as shown.

RELZA J. HESS,
ROBERT K. SEDGWICK.
